US00D606892S

(12) **United States Design Patent**
Zheng

(10) **Patent No.:** **US D606,892 S**
(45) **Date of Patent:** **** Dec. 29, 2009**

(54) **SENSOR OF TIRE PRESSURE MONITORING SYSTEM**

D567,126 S * 4/2008 Zheng D10/86
D588,483 S * 3/2009 Chu D10/85

(75) Inventor: **Yong Zheng**, Shanghai (CN)

* cited by examiner

(73) Assignee: **Suzhou Sate Auto Electronic Co., Ltd.**,
Shanghai (CN)

Primary Examiner—Antoine D Davis

Champlin & Kelly, P.A.

(**) Term: **14 Years**

(57) **CLAIM**

(21) Appl. No.: **29/318,318**

The ornamental design for a sensor of the tire pressure monitoring system, as shown and described.

(22) Filed: **May 16, 2008**

DESCRIPTION

(30) **Foreign Application Priority Data**

Nov. 16, 2007 (CN) 2007 3 0082890
Nov. 30, 2007 (CN) 2007 3 0083783

FIG. 1 is a front elevational view of the claimed design, where the left side elevational view, right side elevational view and rear view are the same as the front view;

(51) **LOC (9) Cl.** **10-04**

FIG. 2 is a top plan view of the design;

(52) **U.S. Cl.** **D10/86; D10/85**

FIG. 3 is a bottom plan view of the design; and,

(58) **Field of Classification Search** D10/83,
D10/85, 86; 73/145–146.8; 116/34 R; 200/61.22,
200/61.25; 340/442–447

FIG. 4 is a perspective view of the design.

See application file for complete search history.

The bottom plan view of item 2 does not form part of the claim design.
